UNITED STATES PATENT OFFICE.

WILLIAM G. REID, OF ROGGEN, COLORADO.

PUMP-ROD LIFT FOR WINDMILLS.

Application filed October 16, 1926. Serial No. 142,083.

This invention relates to devices for raising or lowering pump rods and particularly to mechanism used in connection with a windmill for this purpose.

5 The general object of the present invention is to provide a relatively simple mechanism whereby the pump rod may be lifted by the rotation of the shaft supporting the wind wheel and a further object is to provide 10 means whereby the pump rod may be caused to descend at a greater rate of speed than it ascends.

Another object is to provide a mechanical movement which will secure a reciprocation 15 of the rod from the rotation of a driving shaft and in this connection to provide means whereby a movement of the rod in one direction will be at a greater rate of speed than a movement of the rod in an opposite 20 direction.

Other objects will appear in the course of the following description.

My invention is illustrated in the accompanying drawings wherein:—

25 Figure 1 is a front elevation of the pump rod lift, the wind wheel being omitted;

Fig. 2 is a vertical section on the line 2—2 of Figure 1;

30 Fig. 3 is a transverse section on the line 3—3 of Figure 1, looking in the direction of the arrows;

Fig. 4 is a section on the line 4—4 of Figure 1, looking in the direction of the arrows, the frame and pump rod being omitted;

35 Fig. 5 is a fragmental section on the line 5—5 of Figure 1, the driven shaft and its driven gears being omitted;

Fig. 6 is a fragmental section on the line 6—6 of Figure 1, looking in the direction of the arrows;

Fig. 7 is a section on the line 7—7 of Figure 1;

Fig. 8 is a section on the line 8—8 of Figure 9;

45 Fig. 9 is an elevation of the cushioning means;

Fig. 10 is a fragmental elevation of the pump rod guide showing one manner of mounting the guide rollers.

50 Referring to the drawings 10 designates a steel frame, which is shown as rectangular in form but may be of any suitable form or construction. This may be mounted upon the windmill tower or other support in any 55 suitable manner. Extending through this

frame 10 and mounted in bearings therein is the driving shaft 11 which is driven from the wind wheel, not shown. Carried upon the frame 10 in any suitable manner is a guide 12 having openings 13, these openings having bearings within which are mounted the rollers 14 which bear against the rear face of a pump rod section 15, the front face of which is formed with rack teeth 16.

Also mounted upon the frame 10 is a driven shaft 17 which carries upon it and keyed thereto a relatively large gear wheel 18, see Figure 5. Also mounted upon the shaft 17 and preferably engaged therewith by a set screw 19, is a segment gear 20 and mounted upon the shaft 17 directly opposite the pump rod is a segment gear 21, as shown in Figure 2, this segment gear 21 having teeth over approximately half of its circumference and being mounted for rotation with the shaft 17.

Keved upon the shaft 11 is the pinion 22, see Figure 4, which meshes with the gear wheel 18 at all times and loosely mounted upon the shaft 11 is a pinion 23 which pinion 80 is mounted upon a sleeve 24 which also carries upon it the gear wheel 25 having the same diameter as the gear wheel 21 and having teeth meshing with the rack teeth 16.

The shaft 11 rotates in the direction of the arrow in Figure 1, and power is communicated from pinion 22 to the gear wheel 18, and thus to the segmental gear 21. This segmental gear revolves in the direction of the arrow in Figure 2 and lifts the pump rod until the last tooth of this segmental gear escapes from the teeth on the pump rod. At this time the segment 20 which is rotating in the direction of the arrow in Figure 5, engages the pinion 23 and this 95 rotates the gear wheel 25 in a reverse direction to the segmental gear 21 and causes the descent of the pump rod. Inasmuch as the segment 20 is of relatively large diameter and the gear wheel 18 of relatively large 100 diameter to the pinion 22, it is obvious that the upward movement of the pump rod will be relatively slow and the downward movement of the pump rod relatively fast. After the last tooth of the segmental gear 20 disengages from the pinion 23, the pinion 21 will again engage the rack teeth of the pump rod and this reverses the motion and raises the pump rod. The segmental gear 20 is held to the shaft 17 by a set screw 19 as pre- 110

viously stated so that the exact position of this segmental gear can be determined for the correct operation.

In order to provide for cushioning the downward movement of the pump rod at the end of its stroke and to provide means acting to start the rod back again, I have provided a spring 26 which, as illustrated, is flat and is disposed in the path of movement of the teeth 16 on pump rod 15 and is mounted at the lower end of the supporting frame 10. This spring, as shown in Figure 9, is mounted upon a yoke 27, the ends of which are supported on guide poles 29 surrounded by coiled springs 28 which bear upward against the yoke. The tension of the spring 26 can thus be somewhat regulated. When the pump rod has descended nearly to its full extent, as in Figure 2, the lowest tooth will strike the spring 26 and depress it, as shown in Figure 6, against the resilience of the springs 28. This tension, therefore, will act to "kick back" the pump rod or will have a tendency to start the rod upward. This spring not only cushions and reacts against the pump rod but assists in securing a quick return after the down stroke of the pump rod. This quick return is secured through the use of the large segment gear 20 which engages with the pinion 23 and reverses the movement of the rack. One of the principal objects of this mechanism is that it saves power as well as increases the amount of water pumped, due to the construction of the mechanism and the quick return.

I claim:—

1. A pump rod lift comprising a supporting frame, a constantly operated driving shaft, a counter shaft, a pump rod having rack teeth, intermeshing gear wheels mounted upon the counter shaft and drive shaft, a segmental gear wheel on the counter shaft intermittently engaging the rack teeth, a pinion loosely mounted upon the driving shaft, a second pinion mounted on the driving shaft and meshing with the rack teeth on the pump rod and rotatable with the first named pinion independently of the driving shaft, and a segment gear mounted upon the counter shaft and engaging the first named pinion at a time when the teeth of the first named segment gear are out of mesh with the teeth of the pump rod.
2. A pump rod lifting mechanism for mills comprising a supporting frame, a driving shaft mounted upon the supporting frame, a driven shaft mounted upon the supporting frame, a pump rod having rack teeth, a pinion mounted upon the driving shaft, a relatively large gear wheel mounted upon the driven shaft and meshing with said pinion,

a segmental gear mounted upon the driven shaft and intermittently engaging the rack teeth, a pinion loosely mounted upon the driving shaft, a sleeve carried thereby, a second pinion mounted upon the sleeve and engaging the rack teeth of the pump rod, and a relatively large segmental gear mounted upon the driven shaft and engaging said second named pinion at times when the first named segmental gear is out of engagement with the rack bar.

3. A pump rod lifting mechanism for mills comprising a supporting frame, a driving shaft mounted upon the supporting frame, a driven shaft mounted upon the supporting frame, a pump rod having rack teeth, a pinion mounted upon the driving shaft, a relatively large gear wheel mounted upon the driven shaft and meshing with said pinion, a segmental gear mounted upon the driven shaft and intermittently engaging the rack teeth, a pinion loosely mounted upon the driving shaft, a sleeve carried thereby, a second pinion mounted upon the sleeve and engaging the rack teeth of the pump rod, and a relatively large segmental gear mounted upon the driven shaft and engaging said second named pinion at times when the first named segmental gear is out of engagement with the rack bar, the last named segment gear being adjustable upon the shaft on which it is mounted.

4. In a pump rod lifting mechanism, a supporting frame, a vertically reciprocatable pump rod, the pump rod having rack teeth, gear wheels having teeth engaging the pump rod, a driving shaft, means operated by the driving shaft for rotating said gear wheels in opposite directions to cause the reciprocation of the pump rod, and means for cushioning the pump rod at the end of its downward stroke and causing a return impulse to be transmitted to the pump rod comprising a spring having its free end disposed in the path of movement of the lowest tooth of the pump rod, and a spring supported yoke upon which the spring is mounted.

5. In a pump rod lifting mechanism, a vertically reciprocatable pump rod, a driving shaft, means operated by the driving shaft and causing the reciprocation of the pump rod, and means for cushioning the pump rod at the end of its downward stroke and causing a return impulse to be transmitted to the pump rod comprising a spring having its free end disposed in the path of movement of a portion of the pump rod, and a spring supported yoke upon which the spring is mounted.

In testimony whereof I hereunto affix my signature.

WILLIAM G. REID.
